DISPLAY EASEL

Philip G. Ryan, Brooklyn, N. Y.

Application January 8, 1937, Serial No. 119,613

5 Claims. (Cl. 248—198)

My invention relates to display easels, and has for its primary object to provide an improved device for use in window or counter displays which, while affording the utmost utility and stability for its size, is at the same time unobtrusive and elegant in appearance.

Another object of my invention is to provide an improved display easel, both simple to manufacture and inexpensive: the main supporting frame of which may be stamped from sheet metal, bent to the desired shape, and combined with inexpensive wood molding, having a fine metallic or other finish, constituting the body or visible portion of the device, which molding can 5 be duplicated in metal only at many times the cost thereof.

A still further object of my invention is to provide an improved reversible display easel readily attachable to an article on display, as between 10 the leaves of a book for indicating the price of, or otherwise identifying, such article.

A still further object of my improved display easel is the provision of a primary groove or channel, to accommodate a picture or card of 15 any width consistent with stability of the particular size of easel being used, combined with a secondary slot in which may be carried another identifying marker, such as a cut-out number indicative of the price of an article on display, 20 such marker thus standing out in relief against the background formed by the main card.

Other objects and advantages of my invention will become apparent as the specification proceeds.

With the foregoing objects in view, my invention consists of the novel combination and arrangement of parts hereinafter described in their preferred embodiment, particularly pointed out in the appended claims, and illustrated in the 25 accompanying drawing, wherein like parts are designated by the same reference characters throughout the several views.

In the drawing:

Figure 1 is a perspective view of my improved 30 display easel in upright position;

Fig. 2 is a similar perspective view of the easel 35 reversed;

Fig. 3 is a plan showing a modified form of wings;

Fig. 4 is a perspective side view of the two 40 parts of the invention shown separately prior to assembly;

Fig. 5 is a side view showing the easel carrying 45 cards as for display; and Fig. 6 is a detail view partly broken away of a modified form of support.

Referring to the drawing, my invention consists of a frame portion, stamped from sheet metal in the form shown, which comprises a rectangular, inclined plate 10, having at its opposite sides bent forwardly at right-angles therefrom a 5 pair of wings 11. Spaced from, integral and parallel with said plate 10 is a second similar plate 12, the two plates 10 and 12 being continuous and connected by a U-shaped bend in the metal along their entire bottom edges. The plate 12 10 may be of greater height than the plate 10 if desired to support extra large or heavy cards. These two plates 10 and 12 thus provide a primary display groove or channel 13 therebetween. Integral with and central on the upper edge of 15 the plate 12 is formed a tongue or stand member 14, substantially triangular in shape for stability, which may be bent downwardly therefrom to form a right-angle therewith as shown, and which 20 serves as a prop to support the device in its upright position, or upside down, or upon its sides. Between the wings 11 is set a piece of wood molding 15, half round in cross-section in the form shown (although any shape in cross-section may 25 be used), it being understood that the peripheral contour of the wings 11 shall conform in shape to the particular cross-section of the molding 15 to mask the unfinished ends of the latter. The molding 15 is set flush with the top edge of the plate 10 and is spaced slightly therefrom so as to 30 provide a secondary display slot 16 open at both top and bottom, although the bottom of such slot is closed by contact with the surface upon which the device stands, when upright. The wings 11 35 may be perforated in the stamping operation to permit of fastening the molding 15 therebetween as with nails 17, or the peripheral edges of the wings 11 may be crimped, in which case metal with sufficient spring may be used, to grip the molding 15 as shown clearly at 18 in Fig. 3.

Referring particularly to Fig. 5, a card 19, which may be of any desired width, is shown set in the groove 13 while threaded through the slot 16 is a card 20 bent in half so that its lower half lies partly under molding 15 and in a horizontal 45 plane in front of the easel as shown. The portion of card 20 showing above molding 15 may be in the form of cut-out numbers or other identifying marker or design, while that portion or tab which protrudes in front thereof may be of some other design, carrying descriptive matter pertaining to the article displayed, or to its maker. The portion of card 20 showing above or below 50 may of course be included or omitted as desired; in any case the slot 16 serves to retain the same.

My invention affords special facility to the window-dresser or store-keeper in the matter of placement: with the easel reversed, as shown in Fig. 2, the tongue 14 may be conveniently slid under an article displayed, or, either upright or reversed, between the leaves of a book. When suspended, any card inserted in the slot 16 which is open at the bottom must of course be thick enough to be retained therein by wedging action. The device may be set to depend from the front edge of a shelf, an article displayed and to which the matter carried by the easel refers in that case being placed upon the tongue 14.

Referring to Fig. 6, tongue 14 is omitted and on the opposite sides of plate 12 are formed tabs 21 which, first perforated and fitted with tacks 22, are then doubled back upon plate 12, leaving the tack points protruding rearwardly therefrom, in which form the device may by slight pressure be firmly attached to the edge of a shelf, panel, etc.

While I have described and shown my invention as being made of a combination of sheet metal and wood molding, I also contemplate making the same entirely of metal, or casting the device complete as a molded plastic.

Although the drawing and the above specification disclose the best mode in which I have contemplated embodying my invention, I desire to be in no way limited to the details of such disclosure for, in the further practical application of my invention, changes in the constructional details of the device may be made as circumstances require or experience suggests, without departing from the spirit of the invention within the scope of the appended claims.

What I claim is:

1. A display easel of the character described comprising, a pair of rigid rectangular parallel plates spaced from each other and connected together along only one of their longer edges respectively, wings formed on the opposite shorter side edges of one of the plates, a solid body member held by said wings and spaced from said wing-carrying plate, and means on the other plate for supporting the easel in a plurality of displaying positions.

2. A display easel of the character described

comprising a pair of integral parallel plates spaced from each other so as to provide an unrestricted open groove therebetween, wings formed on the side edges of one of the plates and disposed at right angles thereto, a rearwardly extending prop on the other plate, and a solid member fixed between said wings and spaced from said wing-carrying plate so as to provide a slot open only at the top and bottom thereof.

3. A display easel of the character described comprising, a pair of integral parallel plates spaced from each other so as to provide a groove therebetween, forwardly bent wings on the side edges of one of the plates, a prop on the other plate, and a strip of moulding held by said wings and having a flat surface of approximately the same dimensions as the plates, spaced from, and parallel with said wing-carrying plate so as to provide a slot open only at the top and bottom thereof.

4. A display easel of the character described comprising, a pair of integral flat parallel metal plates spaced from each other so as to provide an open horizontally extending groove therebetween, forwardly bent wings with inwardly crimped edges formed on the opposite ends of one of the plates, a prop formed on and disposed at an angle to the other plate, and a strip of wood moulding between said wings, gripped by said crimped edges, and having one flat surface spaced from said wing-carrying plate so as to provide a vertically extending slot open only at the top and bottom thereof.

5. A display easel of the character described comprising, a pair of integral parallel plates spaced from each other so as to provide an open groove therebetween, a prop formed on and disposed at an angle to one of the plates, wings with crimped edges formed on the opposite ends of the other plate and disposed at right-angles thereto, a strip of moulding having at least one flat surface, said moulding with said flat surface spaced from said wing-carrying plate being disposed between said wings and held by said crimped edges, and said wings conforming in shape to a cross-section of the moulding.

PHILIP G. RYAN.
